UNITED STATES PATENT OFFICE.

EMILE KARL BAOYERLIN, OF LOUISVILLE, KENTUCKY, ASSIGNOR OF ONE-HALF TO CHRISTIAN SCHENK, OF SAME PLACE.

HEATER.

SPECIFICATION forming part of Letters Patent No. 395,200, dated December 25, 1888.

Application filed May 12, 1888. Serial No. 273,732. (No model.)

To all whom it may concern:

Be it known that I, EMILE KARL BAOYERLIN, a citizen of the United States, residing at Louisville, in the county of Jefferson and State of Kentucky, have invented certain new and useful Improvements in Heaters; and I do hereby declare the following to be a full, clear, and exact description of the invention, such as will enable others skilled in the art to which it appertains to make and use the same.

My invention relates to improvements in the class of heaters which may be used for both heating and cooking purposes; and it consists in the several features of construction and combination of parts hereinafter fully set forth, and definitely pointed out in the claims.

The object of my invention is to furnish a heater adapted primarily to the use of a specially-prepared fuel, the composition of which will be the subject-matter of a separate application, which requires no chimney or pipe for draft or smoke escape, and may be moved from place to place in an apartment or railroad-car, as desired.

Referring to the drawings forming part of this specification, Figure 1 is a side perspective view of the heater. Fig. 2 is a vertical sectional view on a medial line from front to rear, showing interior arrangement and construction. Fig. 3 is a detail view of the plate separating the hot-air drum and cold-air drum. Fig. 4 is a plan view of the bottom of the heater. Fig. 5 is a sectional view on a medial line from side to side of the top of the heater after the cap has been taken off.

Similar letters refer to similar parts throughout the several views.

The reference-letter A denotes the outer body or case of the heater.

B is the removable cover or cap of the heater, which may have a central opening in its top, in or over which may be fitted the removable water-reservoir C.

D is a cold-air drum at the bottom of the heater and rising a little way up its sides, having openings d d d in its bottom, which is also the bottom of the heater, and having a close cover, on which the pan d' rests.

E is an air-tight hot-air drum resting on D

and surrounding the inside of the case of the heater, having pipes e e e e—only the upper ends of which are shown in the drawings—passing through it vertically from top to bottom, connecting the cold-air drum D with the circulation and combustion chamber F.

F is a circulation and combustion chamber divided into two compartments by the grate L, and formed by the walls of the cold-air drum D, the hot-air drum E, the heater-case A, and the cap B.

G is a gas-killer consisting of an air chamber or flue, closed at the top and open at the bottom, placed vertically against the walls of the hot-air drum inside the combustion-chamber F, extending nearly the full length of the hot-air drum, having near its top two longitudinal openings, g g, into the upper compartment of the chamber F, while it opens at the bottom into the lower compartment of said chamber just above the ash-pan d'.

H is a gas-escape pipe, passing through the gas-killer G at h and behind it through the hot-air drum to a point lower than the grate, and then outward at right angles, projecting beyond the case A, and provided on the outside with a damper, h'.

I represents a flat plate of metal, which separates the cold-air drum D from the hot-air drum E, and serves as a bottom for E and a top for D, perforated with holes e' e' e' e' for the pipes e e e e, and having a central aperture M, in it corresponding in dimensions to the horizontal sectional area of the chamber F.

f is an opening for fuel, provided with a door.

f' is a draft-opening provided with a check-draft or damper.

C, as figured in the drawings, is a tank or receptacle for water, with attachments to adapt it to serve as an extinguisher; but I do not further describe or claim it here, as I will make it the subject-matter of another application.

J J are handles by which the heater may be lifted.

K designates a damper of suitable construction for closing the apertures d d d in the bottom.

The cap B may be firmly fixed in place by

an arrangement of a slot or groove in the cap engaging a lug on the heater, and the water-receptacle C may be fixed by a similar device.

When it is desired to start a fire in the 5 heater, the cap B is removed and the fuel is placed on the grate and the fire is applied by means of a specially-prepared lighter, the composition of which will be the subject-matter of another application. The top is 10 then replaced, the dampers f' and h' and the apertures d d in the bottom opened, and a rubber tube attached to the pipe H outside the heater. The tube is carried to the fireplace or to the outside of the apartment by 15 the window or door, in order to carry off what fumes may arise from the lighter. As soon as the fuel is well lighted, the rubber tube may be removed and the damper h' closed. When it is desired to keep the fire for some 20 time without replenishing, the dampers K and f' should be closed.

When it is desired to use for cooking a heater of the pattern shown in the drawings, the water-reservoir C is removed and a tin or 25 sheet-iron oven substituted for it. For cooking purposes, however, a lower heater constructed with the same features and combination of parts will be more convenient.

In my heater the shape of the outer case 30 and of the corresponding interior parts may be altered to suit convenience or taste.

Having thus described my invention, what I claim as new, and desire to secure by Letters Patent, is—

1. In a heater for heating and cooking, the 35 combination, with the case A, provided with handles, of the removable cap B, the cold-air drum D, having apertures d d d in its bottom, the air-tight hot-air drum E, the combustion-chamber F, the pipes e e e e, passing 40 through the hot-air drum and connecting the cold-air drum with the combustion-chamber, the gas-killer flue G, and the gas-escape pipe H, substantially as set forth.

2. In a heater for heating and cooking purposes, the combination of a combustion-chamber divided into an upper and lower compartment by grate-bars, an air-tight hot-air drum, a cold-air drum connected with the combustion-chamber by pipes passing through 50 the hot-air drum, and a gas-killer flue, closed at top and having apertures into the upper compartment of the combustion-chamber and open at the bottom into the lower compartment of said chamber, substantially as 55 set forth.

In testimony whereof I affix my signature in presence of two witnesses.

EMILE KARL BAOYERLIN.
